RICHARD WALKER, OF MILFORD, MASSACHUSETTS.

Letters Patent No. 62,168, dated February 19, 1867.

IMPROVEMENT IN LET-OFF MOTION FOR LOOMS.

The Schedule referred to in these Letters Patent and making part of the same.

TO ALL WHOM IT MAY CONCERN:

Be it known that I, RICHARD WALKER, of Milford, in the county of Worcester, and State of Massachusetts, have invented a new and useful Improvement in Let-Off Motion for Looms, of which the following is a full, clear, and exact description, reference being had to the accompanying drawings, making part of this specification, in which—

Figure 1 represents an end elevation of a loom with the improved let-off attached.

Figure 2 is a side elevation of the same.

Figure 3 is a section through the same on the line zz of fig. 1.

Figure 4 is a section through the same on the line xx of fig. 2.

Similar letters indicate like parts in the several figures.

The object of my invention is to provide a means for letting off the warp on the yarn-beam when at a proper tension by means of a positive motion imparted by the backward motion of the lay; and the invention consists in the employment of a sliding-bar provided with two pawls, one being fixed to the said bar and the other vibrating on the same at the opposite end, and so arranged that one pawl will hold a ratchet-wheel which is placed between the two, while the other pawl is passing over a tooth of the same, the two pawls acting on the ratchet alternately. On the shaft that carries the ratchet is a pinion that engages with a gear-wheel on the yarn-beam. Underneath the warp, and in close proximity to the whip-roll, is a pressure-bar extending the whole width of the warp and pivoted to a lever arranged similarly to a scale-beam, and also connected by a series of rods and levers to the aforesaid sliding-bar that carries the two pawls, so that the tension of the warp acting upon the said cross-bar will bring a short connecting-bar, which is hinged to the aforesaid sliding-bar, to a position in which it will be struck by a projection on the sword of the lay, on the backward motion of the latter, and thus impart motion to the sliding-bar and pawl.

Referring to the drawings, G represents the frame of the loom; A is the yarn-beam; and aa represent the warp; B is the whip-roll, over which the warp passes on leaving the yarn-beam. C is a pressure-bar pivoted to a bearer, e , the upper edge of which may be elevated as desired above the level of the whip-roll, by means of a screw, which, passing through a vertical slot in the short arm of the lever D , is pivoted to an arm, E , which is attached to a standard, F , secured to the frame G . To the end of the long arm of the lever D is attached a rod, H , which passes down freely through a guide, I , secured to the frame G . To the rod H , above the guide I , is attached a short arm, g , which may be adjusted higher or lower on the rod H . This arm g passes loosely into a hole in the lever J at h , (fig. 1.) Beneath the guide I , on the rod H , is arranged a spiral spring, k ; its upper end bearing against the said guide and its lower end resting upon a nut, i , which is screwed upon the lower end of the rod H , by which means the degree of tension on the pressure-bar C may be regulated. One end of the lever J is pivoted to an adjustable standard, K , attached to the main frame G , and the other end of said lever is connected by means of an upright bar, L , to one end of a bar, M , as shown in fig. 4, the other end of said bar M being pivoted to the escapement slide R , which has a free longitudinal movement in a supporter, N , as shown in figs. 1 and 4. The supporter N is provided with guides, nn , at each end, for holding the escapement slide, which is slotted near the centre to admit of its free motion on the axle m of the ratchet-wheel P and pinion Q . The supporter N carries an axle, m , on which is borne the ratchet-wheel P and pinion Q , the latter engaging with the gear-wheel W on the yarn-beam. The escapement slide R is provided with two pawls, one of which, p , is firmly fixed to the slide at one end, and the other, r , is pivoted to the opposite end of the slide so as to operate as a single pawl when the warp is wound on the yarn-beam, being prevented from rising too high by a spring, s , and from falling by a pin, t . The supporter N contains in a slot, as shown in fig. 1, a spiral spring, T , one end of which is attached to the escapement slide R , and the other presses against the end of the slot, thus forcing the pawl r towards the ratchet P . Attached to the sword of the lay U , is a projection or hammer, u , which may be rigidly attached, or, passing through the sword, may be connected with a spring, as shown in fig. 4. As the lay is moved backwards the hammer U strikes against the end of the bar M , which forces the escapement slide R towards the ratchet-wheel P , with which the pawl p engages while the pawl r is relieved. When the lay moves forward again the spring T , in the supporter N , throws the escapement slide

back to its former position, and the pawl *r* again engages with the ratchet-wheel, thus allowing but one tooth to pass the pawls at once and letting off a certain amount of yarn at each backward stroke of the lay. The pressure of the warp on the pressure-bar *C* causes the lever *D*, (by means of the rod *H*, the lever *J*, and bar *L*,) to raise the bar *M* to a position to be struck by the hammer *u*. When the pressure of the warp on the bar *C* is insufficient, the end of the bar *M* will fall below the hammer *u*, and consequently the let-off will not take place until the tension becomes sufficient to again bring the proper amount of pressure on the bar *C*. In the escapement arrangement as commonly employed the teeth are liable to slip and break, the escapement passing over occasionally more than one tooth at a time. In my invention such a contingency is not liable to occur, as the motion is positive and the pawls can pass but one tooth at a time.

Having thus described my invention, what I claim as new, and desire to secure by Letters Patent, is—

1. A let-off motion in looms effected by means of a horizontal sliding-bar *R*, provided with pawls, as described, in connection with a ratchet-wheel *P*, the said sliding-bar being operated by the hammer *u* on the lay, which in its backward movement strikes the horizontal intermediate bar *M*.
2. I claim the combination of the pivoted pressure-bar *C*, located as described, with a series of adjustable levers and rods, in such a manner that the tension of the warp upon the pressure-bar will cause a bar, *M*, to be brought in a position to be operated by the backward movement of the lay, and thus operate the escapement slide *R*, substantially as described.
3. I claim regulating the degree of tension which will determine the position of the bar *M*, by means of the series of adjustable bars, levers, and rods, operated by the pressure-bar *C* located below the warp, substantially as described.

In testimony whereof I have signed my name to this specification in the presence of two subscribing witnesses.

RICHARD WALKER.
